L. A. KRUPP.

CONVEYER CONTROL FOR DITCHING MACHINES.

APPLICATION FILED MAY 10, 1915.

1,177,781.

Patented Apr. 4, 1916

FIG. 2.

FIG. 1.

INVENTOR

Leo A. Krupp,
By Cwin, Cwin & Crampton,
his atty.

UNITED STATES PATENT OFFICE.

LEO A. KRUPP, OF FINDLAY, OHIO, ASSIGNOR TO THE BUCKEYE TRACTION DITCHER COMPANY, OF FINDLAY, OHIO, A CORPORATION OF OHIO.

CONVEYER CONTROL FOR DITCHING-MACHINES.

1,177,781.

Specification of Letters Patent. Patented Apr. 4, 1916.

Application filed May 10, 1915. Serial No. 27,096.

To all whom it may concern:

Be it known that I, LEO A. KRUPP, a citizen of the United States, and a resident of Findlay, in the county of Hancock and State of Ohio, have invented a certain new and useful Conveyer Control for Ditching-Machines; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to self adjusting means for the conveyers of excavating or ditching machines of the rotary type.

The object of my invention is the provision, in a machine of the character described, of means which is operable to effect an adjustment of the conveyer relative to the cutting-wheel and its carrying frame, and which is adapted to automatically maintain the conveyer in any predetermined position of adjustment relative to the cutting-wheel during a raising or lowering of the cutting-wheel and its carrying frame.

The invention is fully described in the following specification, and while, in its broader aspect, it is capable of embodiment in numerous forms, a preferred embodiment thereof is illustrated in the accompanying drawings, in which,

Figure 1 is a side elevation of a portion of a ditching machine embodying my invention, and Fig. 2 is an end elevation of the portion of the machine shown in Fig. 1 looking toward the left.

Referring to the drawings, 1 designates the tractor or main machine frame, which is carried by a set of wheels 2, and has the upright guide frame 3 adjacent to its rear end.

4 designates the frame in which the cutting wheel 5 is mounted for rotary movements. The inner end of this frame has engagement with and is guided for vertical movements by the upright frame 3. Cables 6 control the vertical adjusting movements of the cutter wheel carrying frame 4 in a well known manner.

The customary conveyer frame 7 has one end disposed within the cutting wheel 5 and pivoted, as at 8, to the top of the frame 4 at one side thereof and thence extends

across said frame 4 and has its delivery end extended a desired distance beyond the opposite side of the frame 4. The conveyer frame 7 carries rolls 9, 9 at its opposite ends, which guide the course of a conveyer 10.

A boom 11 projects vertically and outwardly from one side of the upright frame 3 over the outer or free end portion of the conveyer frame 7 and is supported in desired position by rods 12, which extend back from the free end of the boom and are connected to the upper end of the frame 3. A sheave 13 is carried by the boom 11 at its free end.

A cable 14, which adjustably supports the free end of the conveyer frame 7, is attached to such frame through the medium of a bail 15, thence passes upward over the sheave 13, thence forward to the upright frame 3, over a sheave 16 carried thereby, thence downward and around a sheave 17, which is carried by the frame 3 near its lower end, thence across said frame and around a sheave 18, which is carried at the opposite side thereof, thence rearward around a sheave 19, carried at the rear end of the tractor frame 1, thence upward over a sheave 20 carried by the cutting wheel carrying frame 4, and then rearward and winds on a control drum 21, which is carried by the frame 4. A hand control wheel 22 is mounted on the shaft with the drum 21. The drum 21 is prevented from turning in a conveyer lowering direction by pawl 90 and ratchet means, as shown at 23.

It is apparent with this arrangement that the position of the conveyer frame 7 relative to the frame 4 and cutting-wheel 5 can be changed, as desired, by a turning of the hand control wheel 22, which will permit a lengthening out or cause a taking up of the cable 14. It is also apparent that when the conveyer has been once adjusted relative to the cutting wheel, such adjustment is maintained irrespective of the raising and lowering movements of the cutting wheel and its carrying frame, thereby obviating the objections incident to the conveyer adjusting means heretofore employed, so far as I am aware, the use of which would cause the cutting wheel and its carrying frame to have raising and lowering movements relative to the outer end of the conveyer when an adjustment of the cutting

wheel was effected, and necessitating a frequent adjusting of the conveyer frame to maintain it in desired material conveying position.

5 I wish it understood that my invention is not limited to any specific construction, arrangement or form of the parts, except in so far as such limitations are specified in the claims.

10 Having thus described my invention, what I claim as new, and desire to secure by Letters Patent, is,—

15 1. In a machine of the class described, in combination, a main frame, a cutting-wheel carrying frame carried by and vertically adjustable relative to said main frame, a conveyer frame pivotally projecting from said adjustable frame, a drum carried by said adjustable frame, a cable connecting the free 20 end of the conveyer frame and said drum, and means having parts carried by said frames and serving to guide the course of said cable for the purpose described.

25 2. In a machine of the class described, in combination, a main frame, a cutting-wheel carrying frame carried for vertical adjustment by said main frame, a conveyer frame pivotally projecting from said adjustable frame, a boom projecting from said 30 main frame and over the outer end portion of said conveyer frame, cable guiding sheaves carried by said boom, main frame

and adjustable frame, a cable guided by said sheaves and attached at one end to the free end portion of said conveyer frame to 35 serve to support the same, and means carried by said adjustable frame and having connection with the other end of said cable, said means being operable to take up or pay 40 out the cable.

3. In a machine of the class described, in combination, a tractor frame having an upright part, a cutting-wheel frame carried by and vertically adjustable relative to the upright part of said tractor frame, a conveyer frame, a boom projecting from said adjustable frame for vertical swinging movements, a boom projecting from said upright frame part over the free end portion of said conveyer frame, a cable winding and control means carried by said adjustable frame, a cable connecting the free end portion of said conveyer frame and said means and serving to adjustably support said conveyer frame, and guide means for said cable having parts carried by said boom, said tractor frame and its upright part, and said adjustable frame whereby the adjustable frame may be raised or lowered without changing the adjusted position of the conveyer frame relative thereto.

55 In testimony whereof, I have hereunto signed my name to this specification.

LEO A. KRUPP.
